BOARDMAN J. HILL, OF DES MOINES, IOWA

INK-CLEANING DEVICE FOR FLAT-BED CYLINDER PRINTING PRESSES

Application filed November 22, 1926. Serial No. 150,023.

In connection with the use of so-called flat bed cylinder printing presses it has heretofore been necessary for the operator at frequent intervals to remove all of the ink distributing rolls and the form inking rolls and clean them by hand with gasoline or the like, and when said rolls are removed to also clean up the ink distributing plate by hand. This operation has been generally known as "washing up" the printing press.

The object of my invention is to provide a simple, durable and inexpensive device in the nature of an attachment that may be readily quickly and easily applied to printing presses of the character described, and whereby the "washing up" process may be automatically effected in a thorough manner by the operation of the printing press and without the removal of any of the rolls from the printing press.

My invention consists in the construction, arrangement and combination of the various parts of the device, whereby the objects contemplated are attained, as hereinafter more fully set forth, pointed out in my claims, and illustrated in the accompanying drawings, in which:

Figure 1 shows a vertical, central, longitudinal, sectional view of a portion of a flat bed cylinder printing press of ordinary construction, having my improvement applied thereto.

Figure 2 shows a detail view illustrating the device for moving the scraper into and out of contact with the ink distributing plate. In this figure the scraper is shown out of contact with the ink distributing plate.

Figure 3 shows an enlarged, detail, sectional view illustrating the spring actuated pin for holding the mechanism which actuates the scraper toward and from the plate into either operative or inoperative position, taken on the line 3-3 of Figure 4.

Figure 4 shows an enlarged, detail, side view of the jointed rod for imparting motion to the scraper actuating mechanism.

Figure 5 shows an enlarged, detail, vertical, sectional view illustrating the ink receiving trough and showing the scraper in position projected down into the trough with

the ink cleaning blade of the trough in position for removing the ink from the scraper.

Figure 6 shows a somewhat similar view illustrating the scraper in contact with the ink distributing plate adjacent to the ink receptacle; and

Figure 7 shows a detail perspective view illustrating the manner in which the ink receiving trough and scraper cleaning device is detachably and pivotally connected to the ink distributing plate.

Referring to the accompanying drawings, I have used the reference numeral 10 to indicate generally the frame of the printing press. Slidingly mounted upon this frame is a type form bed 11 connected with the ink distributing plate 12. The sliding movement is usually effected in presses of this kind by means of a rack 13 applied to the form bed and ink distributing plate, and in mesh with a cog wheel 14 to which an alternating rotary motion is applied in the ordinary manner. At one end of the press there is usually provided an ink receptacle 15 in which there is mounted an ink distributing roller 16, which is rotated during the operation of the press.

In presses of this kind there is also usually provided an ink carrying roll 17 mounted on a bell crank lever 18 connected to a rod 19 which in turn is reciprocated by a part of the operating mechanism of the printing press in any ordinary manner not specifically shown herein. This ink carrying roll 17 moves from position in contact with the roll 16 to position in contact with the ink distributing plate.

Presses of this kind are also usually provided with a series of ink distributing rollers, usually arranged in groups of three, there being two soft surfaced rollers 20 in contact with the ink distributing plate, and a hard surfaced roller 21 contacting with the two soft surfaced rollers of the group.

In presses of this kind there is usually supplied a series of form inking rollers similar in character and arrangement with the ink distributing rollers, the soft surfaced rollers being indicated by the numeral 22 and the contacting hard surfaced roller by the numeral 23, the soft surfaced rolls being in position

to be engaged at times by the flat ink distributing plate, and at other times to transmit the ink thereon to the type forms.

All of the parts previously described are of common construction and of themselves form no part of my present invention, and have been herein illustrated and described to show the manner in which my invention is applied to an ordinary flat bed cylinder printing press.

My improvement comprises a rock shaft 24 mounted in suitable bearings in the frame 10 above the ink distributing plate. Fixed to the shaft 24 is an upwardly extended arm 15 25 to which is attached a contractile coil spring 26 fixed at its other end to the frame 10. Extending downwardly from the shaft 24 is an arm 27 to which there is detachably fixed a scraper 28 which extends transversely 20 across the printing press for the full width of the ink distributing plate. This scraper is preferably made of flexible material such as rubber.

At one end of the shaft 24 is a lever 29 extended downwardly, and pivoted to the lower end of the lever 29 is a rod 30 having its lower end at 31 formed hollow to slidingly receive the upper end of a rod 32. For the purpose of adjustably fixing the relative positions of 30 these rods 30 and 32, I have provided in the part 31 two tapered recesses 33 spaced apart from each other illustrated in Figures 2 and 3, and mounted in the rod member 32 is a spring actuated bolt 34 with a tapered end 35 to enter said recesses. This bolt is provided with a knob 35 at its outer end, and a coil spring 36 is provided for normally holding the bolt inwardly. In use with this device when it is desired to remove the bolt 34 from 40 one of the recesses 33 and put it in the other one, the operator simply grasps the knob 35 and pulls it outwardly against the spring pressure and then slides the rod member 32 to position where the slide bolt will enter the opposite one of the recesses 33.

On the lower end of the rod 32 is a guide fork member 37 which receives a shaft 38 which is constantly rotated during the operation of the printing press in any ordinary manner. Fixed to this shaft 38 is a cam 39, and fixed to the rod 32 is a roller 40 in position to be engaged by said cam. During the operation of the ink removing device, the slide bolt 34 is placed in the lower one of the recesses 33 and when in this position, the cam 39 will engage the roller 40, the effect of which is that when the ink distributing plate is moving toward the left, as shown in Figure 1, the scraper 28 will be elevated above and held in an elevated position above and out of contact with the ink distributing plate and the type form, and upon movement of the ink distributing plate in the opposite direction, and when the ink distributing plate is moved 45 to position directly below the scraper, as

shown in Figure 1, then the scraper is moved downwardly into contact with the ink distributing plate and firmly held in such contact by the operation of the cam 39 until the ink distributing plate passes beneath the 70 scraper.

For the purpose of collecting the ink removed from the press, I preferably provide at the outer end of the distributing plate a combined ink receiving trough and scraper cleaner. This device comprises essentially a trough shaped body portion 41 detachably and pivotally fixed in position below the outer end of the ink distributing plate by means of pivot pins 42 at its sides connected to the ink distributing plate, and slots 43 formed in the sides of the ink receiving trough 41 and extended upwardly and through which bolts 44 are extended and seated in the ink distributing plate. In this connection it is obvious that when the bolt 44 is loosened, the trough may be swung downwardly so that it may be cleaned out, and then if the bolts 44 are removed, the trough may be bodily removed. At the outer end of the ink receiving trough I have extended the outer margin of the trough upwardly and then inwardly toward the ink distributing plate, forming an ink cleaning blade 45, the upper edge of which is substantially flush with the top surface of the ink distributing plate. The operation of this part of the device is as follows:

In Figure 6 the scraper 28 is shown in position in contact with the ink distributing plate, and the latter is shown nearing the end of its movement into the body of the printing press, and a quantity of ink is shown being scraped from the ink distributing plate to position where it will fall into the ink receiving trough. In Figure 5 the position of the parts is shown after the ink distributing plate has moved a small distance to the left, and when in this position, the flexible lower end of the scraper has moved down into the ink receiving trough and the edge thereof, against which the ink was piled, is shown in contact with the ink cleaning blade. Obviously a slight additional movement of the ink distributing plate shown in Figure 5 to 115 the left will cause the ink to be cleaned from the scraper and deposited into the trough.

In practice it is obvious that my attachment may be applied to printing presses now in common use without the necessity of altering or changing any of the operative parts thereof, and may be sold and applied as an attachment with obvious advantages.

After an operation of printing has been completed, and it is desired to "wash up" 125 the press, the operator moves the rod 32 to position where its roller 40 will contact with the cam 39. Then upon each reciprocation of the ink distributing plate, the flexible scraper will engage the plate and scrape the 130

5 ink from it into the trough where the blade itself will be cleaned. Then on the next reciprocation of the ink distributing plate, all of the ink distributing rollers will deposit on the ink distributing plate a portion of the ink contained upon their surfaces, and the portion thus deposited will again be removed by the scraper from the ink distributing plate upon the next reciprocation.

10 During this "washing up" process it is sometimes desirable to apply to the ink distributing plate an ink thinning or dissolving compound such for instance as gasoline. After the press has thus been operated for 15 a period of from three to five minutes, substantially all of the ink has been removed from the flat ink distributing plate, and all of the ink distributing rollers, to such an extent at least that in practice I have found 20 that after using black ink and then "washing up" the press in the manner described, I can apply, say for instance, yellow ink and operate the press in printing yellow color without any traces of the black ink appearing 25 in the finished work.

I claim as my invention:

1. The combination with a printing press having a flat ink distributing plate and a series of ink distributing and form inking 30 rollers, of a flexible scraper above the flat ink distributing plate, means for moving the scraper into engagement with the flat ink distributing plate during the movement of said plate in one direction and elevating said 35 scraper out of engagement with said ink distributing plate during the movement of the latter in the opposite direction, a trough shaped ink receptacle attached to one end of the ink distributing plate in position to receive ink scraped from the said plate and of such size as to permit the flexible scraper to move downwardly into the trough after 40 the end of the ink distributing plate passes the scraper, the side of the trough opposite 45 from the adjacent edge of the ink distributing plate being formed into a blade to engage the side of the scraper and remove ink therefrom and discharge it into the trough, means for pivoting the trough in position 50 so it may swing downwardly away from the ink distributing plate, and means for detachably securing the trough in its elevated position.

2. The combination with a printing press 55 having a flat ink distributing plate and a series of ink distributing and form inking rollers, of a scraper above the flat ink distributing plate, and means for automatically moving the scraper into engagement with 60 the flat ink distributing plate during the movement of said plate in one direction and elevating said scraper out of engagement with said ink distributing plate during the movement of the latter in the opposite 65 direction, said means comprising a pivotal

support for the scraper, an arm fixed to the scraper, a rod pivoted to the arm, a rotatable cam to engage said rod and cause it to be moved in unison with the action of the cam, said rod being formed of two parts slidably connected with each other, and means for securing the rod in either of two positions, one position permitting the cam to operate the rod and the other position holding the rod out of engagement with the cam.

3. The combination with a printing press having a flat ink distributing plate and a series of ink distributing and form inking rollers, of a scraper above the flat ink distributing plate, and means for automatically moving the scraper into engagement with the flat ink distributing plate during the movement of said plate in one direction and elevating said scraper out of engagement with said ink distributing plate during the movement of the latter in the opposite direction, said means comprising a pivotal support for the scraper, an arm fixed to the scraper, a rod pivoted to the arm, a rotatable cam to engage said rod and cause it to be moved in unison with the action of said cam, said rod being formed of two parts slidably connected with each other, means for securing the rod in either of two positions, one position permitting the cam to operate the rod and the other position holding the rod out of engagement with the cam, and a spring for yieldingly holding the scraper away from the ink distributing plate.

4. A device for removing the ink from the ink distributing plate and the ink distributing rollers of a flat bed cylinder printing press, comprising a flat ink distributing plate, a series of ink distributing and form inking rollers, a flexible cleaner mounted on a stationary support and extended across the ink distributing plate from side to side, means for moving the scraper into engagement with the flat ink distributing plate during the movement of said plate in one direction and elevating said cleaner out of engagement with said ink distributing plate during the movement of the latter in the opposite direction, means for holding said flexible cleaner against the surface of the ink distributing plate under pressure to bend the same, said cleaner being disposed at an angle relative to the plate and inclined upwardly from the plate and in a direction toward which the plate is traveling when the cleaner is in engagement with it, and a trough shaped ink receptacle attached to one end of the ink distributing plate in position to receive ink scraped from the plate, a blade arranged at the side of the trough opposite the end of the plate with its upper edge substantially flush with the top of the ink distributing plate, and the width of the trough being such that as the flexible cleaner passes over the trough it will swing down into the trough, and then

when it engages the blade it will scrape the ink from a larger portion of the cleaner than would be possible if the cleaner did not move downwardly into the ink trough.

5. The combination with a printing press having a flat ink distributing plate and a series of ink distributing and form inking rollers, of a flexible cleaner blade mounted above the flat ink distributing plate and extended across the plate, means for moving the cleaner blade into engagement with the flat ink distributing plate during the movement of said plate in one direction and elevating said cleaner blade out of engagement with said ink distributing plate during the movement of the latter in the opposite direction, means for holding the cleaner blade against the top surface of the ink distributing plate under pressure at an angle extending upwardly and in a direction toward that in which the ink distributing plate is moving when the cleaner is in contact with it, and a blade for removing the ink from the cleaner, said blade being spaced beyond the rear of the ink distributing plate with its top edge substantially in line with the top of the ink distributing plate, and whereby the elasticity of the flexible cleaner blade will cause it to move to position to firmly engage the scraper blade and remove the ink from the flexible cleaner blade as it passes beyond the scraper blade.

6. A device for removing ink from the ink distributing plate and the ink distributing rollers of a flat bed cylinder printing press, comprising a flat ink distributing plate, a series of ink distributing and form inking rollers, a flexible cleaner mounted on a stationary support and extending across the ink distributing plate, said cleaner being disposed at an angle relative to the plate and inclined upwardly from the plate and in a direction toward which the plate is traveling when the cleaner is in engagement with it, means for moving the cleaner into engagement with the flat ink distributing plate under pressure to bend the same and during the movement of said plate in one direction, means for moving the cleaner out of engagement with the ink distributing plate during the movement of the latter in the opposite direction, a trough shaped ink receptacle attached to one end of the ink distributing plate in position to receive ink scraped from the plate, and a blade arranged at the side of the trough opposite the end of the plate with its upper edge substantially flush with the top of the ink distributing plate, the width of the trough being such that as the flexible cleaner passes over the trough it will swing downwardly into the trough and firmly and yieldably engage said scraper blade to remove the ink from the lower portion of said cleaner.

7. A device for removing ink from the ink distributing plate and the ink distributing

rollers of a flat bed cylinder printing press comprising a flat ink distributing plate, a series of ink distributing and form inking rollers, a cleaner extending across the ink distributing plate, means for moving the cleaner into engagement with the ink distributing plate under pressure during the movement of said plate in one direction and for moving the cleaner out of engagement with the ink distributing plate during the movement of the latter in the opposite direction, a trough shaped ink receptacle attached to one end of the ink distributing plate in position to receive ink from the plate and a blade at the side of the trough opposite the end of said plate with its upper edge substantially flush with the top of the ink distributing plate, said cleaner being adapted to move into the ink receptacle and engage said plate to remove ink from the cleaner as the blade moves under the same.
